UNITED STATES PATENT OFFICE.

FORTUNATO C. ZANETTI, OF BRYAN, TEXAS, ASSIGNOR OF ONE-HALF TO
F. E. MISTRÖT, OF SAME PLACE.

DESIGN FOR A LAMP-CHIMNEY CAP.

SPECIFICATION forming part of Design No. 20,114, dated August 26, 1890.

Application filed June 25, 1890. Serial No. 356,726. Term of patent 14 years.

To all whom it may concern:

Be it known that I, FORTUNATO C. ZANETTI, a citizen of the United States, residing at Bryan, in the county of Brazos and State of Texas, have invented a new and original Design for a Lamp-Chimney Cap, of which the following is a specification.

My design consists, essentially, of a perforated circular plate having depending at right angles from its circumference perforated arms which near their ends are bent outwardly at right angles and then downwardly at right angles, terminating in triangular points.

In the accompanying drawings, illustrating my invention, Figure 1 is a plan view of a chimney-cap embodying my design. Fig. 2 is a side elevation thereof.

In the drawings, letter A designates the perforated circular plate, and *a* the depending arms integral therewith. These arms *a* form right angles at the points of junction with the plate, and near their ends are bent outwardly at right angles, as at *a'*, and then downwardly at right angles, as at *a''*, and terminate in triangular points *a'''*. The arms, the outward bend, and the triangular points are all perforated.

Between the arms *a* at the circumference of the plate A and a slight distance below the level of such plate are ornamental openings *a⁴*. These are formed of an upper triangular

opening running into a lower circular opening, the lower one opening into the slits between the arms.

In the perforation of the plate A the lines 35 radiate from the central perforation and are grouped in circles or other regular polygons, and in the perforations of the depending arms the same are in line with some line of the perforations of the plate and extending 40 down the middle of the arms; but it is obvious that the essence of my invention is a circular perforated plate having depending arms with offsets ending in triangular - shaped points, the said arms being perforated. 45

I claim—

The design for a chimney-cap herein described and shown, which consists of a perforated circular plate having depending at right angles from its circumference perforated 50 arms which near their ends are bent outwardly at right angles and then downwardly at right angles and terminate in triangular perforated points, as described and shown.

In testimony that I claim the foregoing as 55 my own I have hereto affixed my signature in presence of two witnesses.

FORTUNATO C. ZANETTI.
